UNITED STATES PATENT OFFICE.

AXEL FOLKE CARLSON, OF CAMBRIDGE, MASSACHUSETTS, ASSIGNOR TO REECE SHOE MACHINERY COMPANY, OF BOSTON, MASSACHUSETTS, A CORPORATION OF MAINE.

WIPING MECHANISM.

Application filed July 26, 1926. Serial No. 124,987.

This invention is a novel wiping mechanism adapted to be used on various types of shoe lasting machines, such for example as that shown in my prior Patent No. 1,563,964, 5 granted December 1, 1925, or in any of the prior patents therein referred to. The present invention has reference more particularly to a mechanism for wiping the shoe upper at the heel end, although the novel 10 features may be used in toe wiping mechanisms.

The general object of the present invention is to afford a wiping mechanism for shoe lasting machines operating in a more 15 efficient and convenient manner. A further object is to simplify and render more compact a wiping mechanism of the kind referred to. Other and further objects and advantages will be made clear in the following 20 description of a convenient embodiment of the invention, or will be apparent to those skilled in the subject. To the attainment of the above referred to objects and advantages the present invention consists 25 in a novel wiping mechanism, and the novel features of construction, combination, arrangement and detail herein illustrated or described.

In the accompanying drawings Fig. 1 is 30 a top plan view, shown partly in horizontal section of sufficient of a wiping mechanism to illustrate the features of the present invention.

Fig. 2 is a right elevation of the parts 35 shown in Fig. 1.

Fig. 3 is a central longitudinal vertical section of the mechanism shown in Fig. 1.

The present invention has to do particularly with the operating or wiping movements of the wiper plates, such movements 40 consisting of a bodily advance toward the end of the shoe combined with converging or swinging movements of the wiper plates toward each other; these combined movements carrying the plates over the margins 45 of the shoe at the end and both sides.

The present invention is a development 50 of the operating mechanism for the heel wipers shown in prior patent of Perri No. 1,222,127 of April 10, 1917, Figs. 3 to 8, wherein an operating handle is swung to the left to force toward the shoe the sliding bar or carriage on which the wiper plates are swingingly mounted, thus giving the 55 desired longitudinal movement, while at the

same time this movement of the carriage, operating through transverse levers seen especially in Fig. 8, causes the swinging or converging movements of the wiper plates. Each transverse lever has its outward end 60 fulcrumed to a stationary point while the carriage operates at a middle point of the lever, so that the toothed sector at the inner end of the lever is given a relatively faster movement than that of the carriage so as 65 to operate on the wiper plate and cause its inward swinging movement. Other prior mechanisms having the same general purpose and similar arrangement are the Perri Patents No. 1,420,573 of June 20, 1922, Fig. 70 4, and No. 1,420,574 of the same date, Fig. 7. In each of these prior mechanisms, the connections for causing the swinging movements of the wiper plates are somewhat 75 complicated and are internally accommodated, whereas, as will be shown, the present invention is simpler and more rugged and is arranged largely externally, so as to offer access for adjustment and repair.

As in the prior patents the wiping mechanism hereof may be mounted upon one of a series of carriages movable in different ways for adjustment and operation. The illustration herein commences with a cylindrical carriage 10, which corresponds with 85 the longitudinally tiltable shell 237 or 265 of the bed lasting machines of said Patents Nos. 1,222,127 and 1,563,964, it, therefore, being understood that the cylindrical carriage or shell 10 may be mounted upon a 90 transversely swingable carriage which in turn is mounted upon a bodily sliding carriage, by which the wiping mechanism is brought up to the shoe, this in Patent 1,222,127 being mounted upon a rising support 95 or carriage by which the elevation may be adjusted to conform with the shoe being lasted.

Mounted inside the cylindrical shell or carriage 10 is shown a laterally tiltable carriage 11, 12, 13 capable of being slightly rotated about the longitudinal axis of the shell, so as to alter the tilt of the wiping plane to accord with the under surface of the shoe. This carriage is shown as built 100 up of superposed elements, which together assume a substantial cylindrical shape fitting inside the shell. Thus the lower section 11 of the tilting carriage is surmounted by a middle section 12, which in turn is sur- 110

mounted by the top section 13. The lower section 11 is longitudinally apertured to receive the shank of a heel clamping device, not shown herein, but which may be constructed as in said prior patents. The left or forward end of the middle section 12, being the end nearest to the shoe, is enlarged or widened into a head 14 having an upstanding rim 15 within which are accommodated and supported the wiping plates.

The apex of the shoe and of the wiping plates is indicated at 16. The actual wiping may be performed by thin contour plates 17 secured to the under side of the wiper plates 18. Preferably the plates swing convergingly about the apex 16 as a centre, so that a continuous contour may be preserved during the wiping operations. For this purpose the wiper plates 18 may be mounted as follows:—Each of them has formed in it an arc slot 19 laid out with the apex 16 as a centre. The two curved slots 19 both engage upon a correspondingly curved guide 20, which extends to both sides of the centre line, and is attached to the forward or left end of the wiper plate carriage 21 shown in the form of a longitudinal bar which slides between and is guided by portions of the middle section 12 of the tilting carriage. The mounting of the wiper plates may be completed by an underlying plate 22 preferably attached to the underside of the curved guide 20, and a cover plate 22^a, seen in Fig. 3, preserving the proper relation between the parts during the swinging movements.

From this construction it will be clear that when the sliding carriage or bar 21 is moved to the left, this will bodily advance the wiper plates toward the shoe, and will carry the apex 16 of the wiping contour over the edge of the shoe at the apex. In accordance with this invention it is preferred to slide the carriage 21 manually, in any desired manner, and to utilize the movements of the sliding carriage to cause the swinging movements of the wiper plates, which broadly is the plan of said Patent No. 1,222,127. For these purposes the sliding carriage or bar 21 has formed at its right or outer end, or rigidly attached to it, a bracket piece 23, one part of which stands up to receive connection from the operating lever, and another part of which extends as a lateral arm 24, forming a rigid part of the bar.

The wiping movements may be effected by a handle 25, which is shown as mounted to swing about a fulcrum 26 provided on a bracket 27 secured to the cylindrical shell 10. The lever may have any suitable connection to the wiper bar 21; for example, a stud 28 extending downwardly from the lever by which is swiveled a slotted head or yoke 29 formed with a curved slot 30, while

a horizontal stud or connecting pin 31 engages the upstanding part of the bracket 23 and the slots 30. Thus is afforded a connection permitting the tilting movements of the elements inside the cylindrical shell, and giving an operating connection such that when the handle 25 is thrown to the left or right, it gives effective actuation to the wiper bar 21 in the same direction.

The swinging movements of the wiper plates toward and from each other may be effected solely from the longitudinal movements of the carriage or bar 21, irrespective of the manner of producing such movements.

Referring to Figs. 1 and 3 each wiper plate 18 is shown as connected by a link 32 to the cross piece or head 33 of a T-shaped actuating bar 34, shown confined between parts of middle section 12 beneath the wiper carrying bar 21. The links 32 may have flat ball and socket connections to the wiper plates and head respectively so that the entire mechanism may be accommodated flatly between the underlying and covering elements. When the actuator bar is moved relatively to the left, this manifestly will cause the wiper plates to swing toward each other. This actuating movement of the bar 34 must be at greater speed than the carrying movement of the bar 21, just as the small toothed levers in said Patent No. 1,222,127 at their inner ends, move faster in order to swing the wiper plates. A suitable connection from the carrier bar 21 to the actuator bar 34 for this purpose may be as follows:—

A bracket 35 is shown attached to the tilting carriage 11—13, and this bracket is substantially stationary during the wiping operation. Pivoted at the rear end of the bracket 35 is what may be termed a gear sector 36 comprising a lever 37 carrying a curved rack 38 at its outer end. The lateral extension or arm 24 of the carrier bar 21 is shown connected by a link 39 to an intermediate part of lever 37. By this arrangement the advancing movement of the carrier bar causes the swinging of lever 37 and the consequent movement of the curved rack 38 at a relatively faster speed. The rack 38 is shown engaging a rack 40 secured at the upper side of the actuator bar 34, so that for each unit of forward movement of the carrier bar, the actuator bar will move a greater distance, and therefore, acting through links 32 will cause the converging swinging movements of the wiper plates.

When the operating handle 25 is retracted completely to the right, both of the bars 21 and 34 will be in their most retracted positions, as shown, and the mechanism in readiness for wiping operation. It is sometimes desirable to adjust initially toward or from each other the wiper plates, and this may be done through the adjusting connection 41

connecting the rack 40 with the actuator bar. By loosening the connection the bar may be shifted slightly endwise to change the initial contour according to the width of the 5 shoes. When the rack is again secured in place the mechanism is in readiness for wiping operation, the forward movement of the hand lever forcing the carrier bar and wiper plates bodily forward, while the lateral connections from the carrier bar, acting through 10 the lever 37, give the relatively greater motion to the actuator bar, in order to cause the simultaneous swinging of the wiper plates as described.

15 It will be noted that the connections from the carrier bar to the actuator bar are exterior and easily accessible for inspection and adjustment. They are simple, rugged and effective. They are compact and arranged at the side away from the operator 20 so as not to impede his operation of the machine. A single multiplying lever or toothed sector serves to give the increased movement to both wiper plates.

25 There has thus been described a wiping mechanism for shoe lasting machines embodying the principles and attaining the objects of the present invention. Since various matters of arrangement, combination, 30 design and operation may be modified without departing from the principles of the invention, it is not intended to limit the invention to such matters, except to the extent set forth in the appended claims.

35 What is claimed is:—

1. Wiping mechanism for shoe lasting machines comprising a frame, wiper plates movable as a whole toward and from the shoe and swingable toward and from each other,

a longitudinally movable carrier arranged 40 to carry the wiper plates toward and from the shoe, a longitudinally movable actuator for swinging the wiper plates toward and from each other, an operating member for longitudinally moving the carrier toward 45 and from the shoe, and a separate connection between the carrier and the actuator for moving the actuator to swing the wiper plates toward and from each other.

2. Wiping mechanism as in claim 1 and 50 wherein the connection from the carrier to the actuator comprises a lever arranged laterally of the actuator with its far end fulcrumed to the frame and a connector from the carrier to an intermediate point on the 55 lever, whereby the movement of the carrier is increased to a faster movement of the actuator.

3. Wiping mechanism for shoe lasting machines comprising wiper plates movable as a 60 whole toward and from the shoe and swingable toward and from each other, a longitudinally movable carrier arranged to carry the wiper plates toward and from the shoe, a longitudinally movable actuator for swinging the wiper plates toward and from each other, an operating member for longitudinally moving the carrier toward and from the shoe, and a separate connection between 65 the carrier and the actuator for moving the actuator to swing the wiper plates toward and from each other, consisting of a toothed sector, a rack on the actuator engaging the sector and a pivoted connector from the carrier to the sector for swinging it. 70

In testimony whereof, I have affixed my signature hereto.

AXEL FOLKE CARLSON.
